KNIFE OR SIMILAR ARTICLE OF FLATWARE

Carl Mertens, Solingen, Germany

Application October 6, 1955, Serial No. 38,250

Term of patent 3½ years

(Cl. D22—3)

FIG. 1

FIG. 2

Fig. 1 is a top plan view of a knife showing my new design; and

Fig. 2 is a side elevational view thereof.

The sides opposite to those of Figs. 1 and 2 are conventionally plain.

I claim:

The ornamental design for a knife or similar article of flatware, as shown and described.
